Specification of Letters Patent.

Patented May 30, 1916.

Application filed February 15, 1916. Serial No. 78,378.

To all whom it may concern:

Be it known that we, HENRY B. OATLEY and NEAL TRIMBLE MCKEE, both citizens of the United States, residing, respectively, at 5 Flushing, county of Queens, State of New York, and at Yonkers, county of Westchester, State of New York, have invented certain new and useful Improvements in Superheaters, of which the following is a 10 specification.

Our invention relates to superheaters, and particularly to the type known as smoke tube superheaters, its object being the provision of an arrangement whereby 15 certain heat losses possible in former arrangements are minimized or wholly obviated, whereby the steam is more efficiently superheated, deposits of soot and cinders prevented, and the friction losses reduced. 20 With superheaters of this type, used principally in connection with locomotives and comprising, as is understood by those familiar with the art, a loop or loops located in flues, the pipes carrying the steam are exposed to the most intense heat near the firebox end of the flues. From this point forward the combustion gases are gradually cooled by the surrounding water as they travel forward until their temperature be- 25 comes, under certain circumstances, lower than that of the steam traveling in the same direction inside of the last leg of the superheater unit. This happens particularly where the flues are of relatively great 30 length, and is objectionable for the reason that the superheated steam again gives up part of its heat to the combustion gases which then leave the flues at a temperature 35 too high for best economy. The present 40 invention reduces this effect to a minimum. Even where from the conditions of the case the danger of the superheated steam again losing part of its heat to the surrounding gases is absent, the present arrangement 45 marks an improvement in that most of the heat transfer from the hot gases to the steam occurs under the most favorable conditions from a thermodynamic standpoint, that is on the counterflow principle. By 50 reducing the number of reversals which the steam experiences in its course through the element, the friction losses are considerably reduced.

We are aware that others have known

of the loss of efficiency above pointed out 55 and its cause, and that arrangements have been proposed to obviate it; and to obtain the advantages of counterflow heating, but as far as we know none of the prior inventions has used the present or analogous 60 means.

In the drawings which form part of the present specification and which illustrate constructions embodying the underlying principle, Figure 1 represents, partly in 65 section and partly in elevation, a superheater unit of the preferred form of our invention together with so much of the adjacent parts of the boiler and headers as is necessary to show the arrangement relative 70 to these parts; Figs. 4, 6, and 8 show modifications; while Figs. 2, 3, 5, 7, and 9 show sections taken on lines 2-2, 3-3, 5-5, 7-7, and 9-9 respectively. In all of the figures the arrows indicate the direction of 75 the steam and gas flow.

Referring first to Figs. 1, 2 and 3, reference numerals 1 and 2 designate respectively the saturated and superheated steam headers, while 3 designates a flue within 80 which is located a superheater unit. In the arrangement hitherto most extensively used the part of the unit lying within the flue is made up of four lengths of pipe connected 85 appropriately to each other by return bends and to the two headers in such manner that the steam, leaving the saturated steam header, traverses the four lengths successively, thereafter passing to the superheated steam header, whence it is carried to the en- 90 gine cylinders. In the present arrangement, as illustrated in Figs. 1, 2, and 3, the pipe 4 leading from the saturated steam header is subdivided at 5 into three parts, 8, 9, 10, each of substantially the same diameter as pipe 4, 95 and reunited into a single pipe 4' at or near the rear end of the flue 3. The pipe 4' is joined by return bend 6 to the length 7, which is also of substantially the same 100 diameter as pipe 4, and the front end of which is continued and attached to superheated steam header 2.

The operation of the device will be evident. Steam is carried from the steam dome or other desired point to the header 105 1 by the usual means known to those familiar with the art, and unnecessary to illustrate or describe here. Passing thence

by pipe 4 it is in pipes 8, 9, and 10 subdivided into three separate streams which re-unite at the rear, and comes forward through the pipe 7 and to header 2 as a single stream. The cross-sections of pipes 8, 9, 10 and 7 being substantially the same the steam travels at a comparatively slow rate toward the fire-box end of the flue, the principal part of the heating occurring during this 10 passage. The return through pipe 7 occurs very rapidly, the single pipe carrying all the steam. The chance for transfer of heat from the superheated steam to the combustion gases in the front part of the flue, 15 where the latter have been cooled by the surrounding water to a temperature below that of the superheated steam, is correspondingly small. The heating, on the other hand, in the other three pipes has occurred under 20 conditions conducive to high efficiency. Manifestly the number of streams into which the ingoing steam is subdivided may be some other number than three; while the headers need not be arranged as shown, but 25 may have any other preferred positions. It is of course understood that there are any desired number of such units, each occupying a flue.

Figs. 4 and 5 illustrate a modification, 30 showing the inventive idea applied to a form, wherein the steam, instead of being carried to the superheated steam header 2 after traversing the pipes in flue 3, is carried through a second set of pipes lying in 35 a second flue, 3', and then to the header 2. The unit is here shown as comprising two in-carrying branches, 8' and 9', springing from the single pipe 4 at point 11, and re-uniting into single pipe 7 at point 12; the 40 arrangement in the second flue being similar. Instead of dividing the steam on its way toward the fire-box into several streams and thus retarding the flow in that direction relatively to that in the opposite direction, the steam may be carried in the former 45 direction by a pipe larger in diameter than the one by which it is returned toward the header. Such an arrangement is shown in Figs. 6 and 7. The steam travels inward 50 slowly through pipe 8 and out comparatively fast through pipe 7, this being repeated in the second flue, after which the steam goes to header 2. Figs. 8 and 9 illustrate the same principle applied to a 55 field tube arrangement, the two coaxial elements 8 and 7 of which are so proportioned that the annular space 13 between them is larger than the space in the inner one. In the latter two arrangements the same advantage is obtained of returning the steam 60

rapidly to the front from the fire-box end, though the heating of the steam on its inward course is not performed as efficiently.

An advantage incidental to all the forms of unit illustrated over previously suggested forms in which coiling or looping the ingoing pipe for the purpose of lengthening the path was resorted to is, that there are no abrupt changes in the cross-section for the gases and the liability of soot and cinder deposits is correspondingly reduced.

It will be evident that various other modifications may be made within the spirit of the following claims.

We claim—

1. In a superheater of the class described, a unit comprising two portions carrying the steam toward and from a source of heat respectively, the former portion having the greater cross-sectional area.

2. In a superheater of the class described, a unit comprising two portions carrying the steam toward and from a source of heat respectively, the former portion comprising a plurality of divisions the combined cross-sectional area of which is greater than that of the latter.

3. In a boiler provided with heating tubes carrying products of combustion, the combination with one or more of said tubes of a superheater unit of the class described located in said tube or tubes and comprising portions carrying steam in directions against and with the current of the products of combustion respectively the former portion or portions having a greater cross-sectional area than the latter.

4. In a boiler provided with heating tubes carrying products of combustion, the combination with one of said tubes of a superheater unit of the class described located in said tube and comprising two portions carrying steam in directions against and with the current of the products of combustion respectively, the former portion having a greater cross-sectional area than the latter.

5. In a boiler provided with heating tubes carrying products of combustion, the combination with one of said tubes of a superheater unit of the class described located in said tube and comprising two portions carrying steam in directions against and with the current of the products of combustion respectively, the former portion being subdivided into a plurality of parts each of substantially the same cross-sectional area as the latter portion.

HENRY B. OATLEY.
NEAL TRIMBLE MCKEE.
